P. J. LE SUEUR,
BREAST DRILL,
APPLICATION FILED DEC. 7, 1917.

1,343,370.

Patented June 15, 1920.

Cecil P. Alderson.

Philip Joshua Le Sueur

UNITED STATES PATENT OFFICE.

PHILIP JOSHUA LE SUEUR, OF BRIGHTON, ENGLAND.

BREAST-DRILL.

1,343,370.

Specification of Letters Patent. Patented June 15, 1920.

Application filed December 7, 1917. Serial No. 205,994.

To all whom it may concern:

Be it known that I, PHILIP JOSHUA LE SUEUR, a citizen of the United States, at present residing at Brighton, county of Sussex, England, have invented a new and useful Improvement in Breast-Drills, of which the following is a specification.

The principal object of this invention is to provide a lightly built and cheap form of breast drill with an efficient form of feed for automatically forcing the drill into the metal or object to be drilled.

A special feature of the invention is the arrangement of parts whereby the depth of the cut of the drill can be quickly adjusted rendering this device specially useful where small and large drills have to be used by the operator.

Another feature of the invention is the lightness and simplicity of the automatic feed device and the facility with which the parts can be removed, or thrown out of gear.

Another important feature of the invention is the smoothness and evenness of the automatic feed, which enables the operator to avoid the breakage of drills and leaving both his hands free to operate and steady the breast drill.

Referring to the drawings:

Figure 1 is a front elevation showing all the main features.

Fig. 2 is a perspective view of the "bearing" riveted to the lever in which works the ratchet, showing the action of the ratchet on the ratchet wheel.

Fig. 3 is also a perspective view of the ratchet pivotally connected with the "bearing" showing the action of the ratchet on the ratchet wheel.

Fig. 4 is a sectional elevation of bearing, lever, and frame and end elevation of ratchet and ratchet wheel.

Fig. 5 is a front elevation of lever showing the adjustable slide piece for lengthening the lever.

Fig. 6 is half sectional, half end elevation of bearing, frame, and gear wheel.

Referring to the drawings: 1 designates the iron frame of the breast drill provided with the usual body rest 2.

The drill 3 is held in position by the ordinary "chuck" 4.

The "feed rod" 5 is movably secured to the brace frame by the bearings A. At the outer end of the feed rod is the drilling ta-

ble 6, which is designed to slide longitudinally on the feed rod and is rendered non-turnable relative to the feed rod by the thumb screw 7, the end of which engages 60 with the groove D in the feed rod. The nut 8 retains the drilling table in position.

The feed screw 16 which is provided with a ratchet wheel 18 and the thumb screw 19 integral therewith, is pivotally attached to 65 the frame, the shank 21 engaging the bearing 22. The threaded portion 16 engages a threaded hole F in the feed rod.

The lever 25 (which may also be described as a lifting plate) is pivotally secured to 70 the frame by the screw 26. The lever extends along the frame of the breast drill and is operated by the lifting or bearing pins 27 which project from the drive wheel 28. The bearing 30 (detail Fig. 2) preferably riveted to the lever by the rivets H in which works the ratchet 32, pivotally mounted on the rivet 33 and is kept in resilient contact with the ratchet wheel 18 by the spring 34 which is secured in position by the rivets 35. 75 The spring 36 retains the lever in position. The plate 38 riveted to frame keeps the lever close to the frame.

In using the breast drill the operator turns the drive wheel in the usual manner. 85 The lifting pins 27 on the drive wheel lift the end of the lever 25 and with it the ratchet 32 which engages the ratchet wheel and turns the feed screw, which acts on the feed rod 5 and forces the drilling table and 90 with it the object to be drilled against the point of the drill. The lifting pins 27 are screwed into the drive wheel and are detachable.

In order to regulate the depth of the 95 "feed" I have provided the snail eccentric 40 which is pivotally secured to the brace frame by the screw 42. The slot 44 allows the screw 46 to hold it in position. It is obvious that by turning the snail eccentric 40 100 and shortening the contact of the lever 25 with the pins 27, the action of the lever and ratchet on the forcing screw 16 will give the drill a shallow feed. The snail eccentric is also capable of throwing the lever out of 105 gear with the pins 27. The snail eccentric acts also as a stop piece for the lever, the spring 36 keeping the lever in contact with the snail eccentric 40.

Referring to Fig. 5 it will be seen that 110 the lever 25 is provided with a slide piece 48. This slide piece is adjustable and is

designed to engage the snail eccentric 50, shown mounted in juxtaposition to the central portion of the drive wheel (Fig. 1). This snail eccentric is designed as a slow feed for heavy drilling. The slide piece is adjustable relative to the lever by the slot 51 and the screw 52. The snail eccentric is screwed on to the threaded part of the spindle 53, the drive wheel is secured in the same manner, the spindle being retained in position in the bearing 55 in the frame by the screw 56 (detail Fig. 6).

The projection 58 on the drilling table and the projection 59 on the frame are designed to engage with the chain 60. This chain is designed to support the drilling table in heavy drilling and it may be adjusted by a screw attachment on the frame of the brace to tighten the chain. It is understood that minor changes may be made without departing from the scope of the invention. The drilling table may be of various forms to suit different kinds of work.

With this form of feed device a shallow or deep "feed" may be obtained. Given a large ratchet wheel with fine teeth the lever may be adjusted so that three teeth of the ratchet wheel 18 may be moved forward at each stroke of the lever. By another adjustment of the stroke of the lever one tooth "only" of the ratchet wheel may be moved forward. This is important—for the normal feed of a feed screw for a drilling press is the thirty fifth part of a "turn" of the forcing screw for each rotation of the drill. When an operator is using a breast drill (often in a difficult place) it is almost impossible to turn a feed attachment by hand sufficiently fine—to prevent the drill from jamming up which means that the operator will probably break his drill, as the slightest side movement of the operator will break a drill. The operator needs both hands to steady the breast drill.

The feed screw 16 in the present design of the machine is provided with a left hand thread.

Attention is called to the arrangement of the lifting piece or lever 25 which is specially designed to avoid a circular motion where the ratchet 32 contacts with the ratchet teeth on the feed screw. The lifting piece 25 is designedly attached to the frame of the drilling brace by the screw 26 at a point above or beyond the feed screw; which method causes the ratchet 32 which is pivotally attached to the lifting piece 25 to act in

alignment with the ratchet teeth on the feed screw giving a remarkably easy motion free from jar. A lever connected pivotally with the frame by a bearing midway of its length could of course be used but the circular motion would be too pronounced.

Referring to the drawings Fig. 6 illustrates the preferred method of mounting the snail eccentric on the spindle of the drive wheel. The snail eccentric could of course be mounted on the outer end of the spindle on the reverse side of the frame, and the lever 25 also on the reverse side of the frame. In this case the forcing screw 16 would be provided with a right hand thread. An ordinary cam could of course be employed in place of the snail eccentric but the snail eccentric is the most advantageous form.

What I claim is:

1. A breast drill comprising a frame, a drill spindle rotatively mounted therein, and having a bevel pinion thereon, a hand wheel mounted on the frame, and having gear teeth for engagement with the pinion, a rod slidably mounted on the frame, and having a work table attached to the lower end, a feed screw in engagement with said rod, a ratchet wheel mounted on the feed screw, ratchet mechanism mounted on the frame for actuating the feed screw, and a cam on the said geared hand wheel for operating said ratchet mechanism.

2. A breast drill comprising a frame, a drill spindle rotatively mounted therein, and having a bevel pinion thereon, a hand wheel having gear teeth mounted on the frame for engaging the pinion, bearings in the frame, a rod slidably working in said bearings, and having a work table attached to the lower end, a feed screw in engagement with said rod, a ratchet wheel mounted on the feed screw, ratchet mechanism mounted on a lever or lifting piece, said lever pivotally attached to the frame above or beyond the ratchet which engages the ratchet wheel, a spring suitably connected with the frame for holding the lever in position, an adjustable stop piece for regulating the stroke of said lever, and means on said geared hand wheel for operating the feed mechanism and giving said rod and the feed table a longitudinal motion.

PHILIP JOSHUA LE SUEUR.
